(57) **CLAIM**

The ornamental design for a luggage wheel housing with a wheel, as shown and described.

DESCRIPTION

FIG. 1 shows a front perspective view of a luggage wheel housing with a wheel;

FIG. 2 shows a front elevation view of the luggage wheel housing of FIG. 1;

FIG. 3 shows a right elevation view of the luggage wheel housing of FIG. 1;

FIG. 4 shows a rear elevation view of the luggage wheel housing of FIG. 1;

FIG. 5 shows a left elevation view of the luggage wheel housing of FIG. 1;

FIG. 6 shows a top view of the luggage wheel housing of FIG. 1; and,

FIG. 7 shows a bottom view of the luggage wheel housing of FIG. 1.

The broken lines showing the yoke of the luggage wheel are for the purposes of illustrating environment and form no part of the claimed design.

1 Claim, 5 Drawing Sheets
